UNITED STATES PATENT OFFICE.

CYRIL LESLIE WILLIAM TUCKER, OF PICCADILLY, WESTMINSTER, ENGLAND.

LATHE.

1,200,053.

Specification of Letters Patent.

Patented Oct. 3, 1916.

Application filed February 24, 1916. Serial No. 80,214.

To all whom it may concern:

Be it known that I, CYRIL LESLIE WILLIAM TUCKER, a subject of the King of Great Britain, residing at 8 Brick street, Piccadilly, Westminster, England, have invented 5 new and useful Improvements in Lathes, of which the following is a specification.

This invention relates to semi-automatic high speed lathes of the kind provided with 10 a tool holder carrying a plurality of tools and capable of rotating about an axis parallel to the axis of the headstock spindle or mandrel to bring each tool into its operative position, such rotation being determined by 15 stops, and in which the work is moved toward and away from the said tool holder during the operation of the various tools, such movement also being determined by stops, the object of the said invention being 20 to provide a lathe of this type which is of simpler construction and cheaper to manufacture than such lathes as hitherto constructed.

In the accompanying drawing:—Figure 1 25 is a sectional side elevation of a lathe constructed according to my invention. Fig. 2 is a sectional plan of the same, and Fig. 3 is an end elevation. Fig. 4 is a section on the line 4—4, Fig. 1. Fig. 5 is a side view of a 30 modified detail, and Fig. 6 is a sectional view at right angles to Fig. 5.

a is the lathe bed which I form of a round bar clamped in brackets or uprights *b*, *b*, the upper portions of which constitute a 35 headstock and provided with bearings *c*, *c* for the mandrel or spindle *d*. This mandrel, which is preferably tubular and provided with a jaw or other chuck, not shown, at the end *d*¹ to hold the work to be operated upon, 40 has the driving pulley *e* loosely mounted upon it between collars *e*¹ and is provided with a dog (or dogs) *e*² designed to coöperate with another dog *f* (or dogs) on what I term a driving plate *f*¹ keyed to the mandrel so as to rotate therewith, but capable of 45 longitudinal movement on the keys which are indicated at *f*². When the two dogs *e*² and *f* are in engagement motion will be communicated to the mandrel *d* from the pulley *e*, while when the mandrel is moved longitudinally so as to disengage the said dogs, 50 the rotation of the driving plate and of the mandrel will cease.

The motion of the driving plate *f*¹ by 55 hand, to cause the engagement and disengagement of the dogs *e*² and *f* is effected by

a sliding handle *g* through the medium of a segment *g*¹ engaging a groove *g*² in the said driving plate.

The longitudinal movement of the mandrel *d* for screw cutting or other purposes is effected by means of externally screw-threaded sleeves fixed to the said mandrel and designed to be engaged by sectional nuts or chasers mounted on the headstock. Where 60 two threads of varying pitch are required upon a single article to be machined two of such screw threaded sleeves of the required pitch are secured to the mandrel, as indicated at *h*, *h*¹, the sectional nuts or chasers *i*, *i*¹ being carried upon the opposite ends of pivoted levers *j*, two of which levers are arranged on opposite sides of the mandrel. These levers are pivoted to the headstock at 65 *j*¹, *j*² at a point midway between their ends so that when one set of chasers, for instance, the chasers *i* are engaged with the screw threaded sleeve *h*, the other chasers *i*¹ are moved away from their screw threaded sleeve *h*¹ and vice versa. For locking either 70 of the chasers *i* or *i*¹ in engagement with their respective screw threaded sleeves a pair of levers *k*, *k* on a common shaft *k*¹, pivoted to the headstock are employed, the said levers bearing against the outer surfaces of the 75 levers *j*, *j*¹ which are provided with the double inclines as shown, so that if the levers *k* be moved either to the right or left they will ride against the inclined surfaces and cause one end of the said levers *j* to move 80 toward the mandrel, while the other ends will be moved away from the mandrel. In the drawing the levers *k* are shown in the intermediate position in which neither chaser is in engagement with its screw threaded sleeve, and for the purpose of manipulating 85 the said levers *k* one of them is extended upwardly, as indicated at *k*², to constitute a handle.

In order that the mandrel *d* may be moved longitudinally by hand I employ a forked lever *k*³ carrying the ring segments *k*⁴ located in the groove of a collar *k*⁵ fixed to the mandrel, the said forked lever being fulcrumed at *k*⁶ to one end of a link *k*⁷, the other end of which is pivoted at *k*⁸ to the head stock.

l is the tool holder which is fixed to a sleeve *l*¹ rotatable upon one end of the bed bar *a*, the said tool holder being of disk shape and provided with a groove *m* upon its periphery to carry a series of micrometer

stops m^1 which serve to determine the position of the tool holder circumferentially as it is partially rotated from time to time to bring the several tools which it carries into 5 their operative position.

The groove m is advantageously of T-form with which the head of a bolt m^2 engages, the said bolt passing through the body of the stop m^1 which is of semi-circular form and adapted to seat itself on the periphery of the tool holder l which is correspondingly formed hollow to receive it, the bolt m^2 being secured by a suitable nut as indicated.

15 Projecting from the body of the stop m^1 in the plane of the disk l is a screwed stud n upon which is screwed a grooved collar n^1 and secured thereon by a lock nut n^2 , the collar n^1 forming the stop proper. The 20 stops m^1 coöperate with a fixed stop o which is in the form of a lever pivoted at o^1 to a bracket o^2 secured to the table or other surface to which the brackets b of the lathe are secured. The said lever o is formed at 25 its upper end with a tooth o^3 designed to engage either of the grooved collars n^1 to hold the tool holder in the required position for use.

To facilitate the operation of the lever o 30 it is provided with a handle o^4 for disengaging it from the grooved collars n^1 , a spring o^5 being arranged on the bracket o^2 and bearing against a tail on the said lever to hold the tooth o^3 in engagement with the 35 grooved collars n^1 .

For clamping the tool holder rigidly when the lever o is engaged with either of the micrometer stops m^1 , I advantageously provide a screw p engaging a screw threaded hole in the bar a , the head of the screw, which is formed with a suitable operating handle p^1 , bearing against a washer p^2 , one face of which is in contact with one face of the disk l , so that when the said handle 40 p^1 is turned in one direction it will cause the washer to exert great pressure upon the disk l and thus clamp it rigidly to the bar a .

50 q, q indicate portions of some of the tools or of their holders proper, the shanks q^1 of which are fixed in an endless slot r in the disk l , this slot being formed by making the outer part of the said disk separate from the inner part, as clearly shown in 55 Fig. 3, and it enables a tool to be adjusted to any required position around the disk l instead of being limited to certain positions as has hitherto been the practice where the tools are carried in holes in the disk. Although 60 the disk l is, by the formation of the slot r , formed in two independent parts they are nevertheless maintained concentric and locked together by the shanks q^1 which are all made of one gage so as to form distance pieces between the two parts, the 65

tightening nuts q^2 on the said shanks locking the parts of the disk firmly together by clamping them between shoulders q^3 on the parts q and washers q^4 .

In order that the travel of the mandrel d , 70 under the action of either of the feed screws h or h^1 , shall in all cases agree with the duty to be performed I provide in relation with each tool a stop s in an endless slot s^1 in the tool holder l against which stop a rod t , 75 carrying the handle g , impinges when the driving plate f^1 has been longitudinally moved to that extent. The further longitudinal movement of the said driving plate is thus arrested whereby after a further 80 definite movement of the mandrel d , with relation to the driving plate, has taken place, the dogs e^2 and f will become disengaged and the rotation of the mandrel consequently cease.

85 In some cases it may be necessary to impart a slight rotary motion to the disk l , for instance, when cutting screw-threads, in order that the chasing tool may be advanced to cut deeper into the work and for this purpose the pivot o^1 of the stop o may be formed or provided with an eccentric u as indicated in Figs. 5 and 6 on which the said stop is pivoted. By the rotation of this eccentric it will be seen that the stop o when 90 in engagement with the disk l will cause a slight rotary movement of the said disk. For effecting this rotation of the eccentric u the pivot o^1 is provided with a handle v .

Claims:

1. In a semi-automatic lathe the combination with a longitudinal movable mandrel and a headstock carrying the said mandrel, of a rotary tool holder comprising an inner disk part and an outer ring section of larger 105 internal diameter than the disk so that a space is left between the two parts which constitutes a slot, and tools or tool holders having shanks fitting into the said slots and constituting distance pieces and clamping 110 means.

2. In a semi-automatic lathe the combination with a longitudinally movable spindle and a headstock carrying the said spindle of a rotary tool holder made in two parts 115 and comprising an inner disk section and an outer ring section provided with a peripheral slot and of adjustable stops designed to be fixed in the said slot.

3. In a semi-automatic lathe the combination of a fixed headstock, a mandrel longitudinally movable therein, a rotary tool holder having a peripheral slot, adjustable stops fixed in the said slot and a fixed stop with which the peripheral stops are 120 designed to engage, the said fixed stop being hinged to allow of its being moved into, or out of, the path of the peripheral stops when the tool holder is rotated.

4. In a semi-automatic lathe the combination 125

tion of a fixed headstock, a mandrel longitudinally movable therein, a rotary tool holder having a peripheral slot, adjustable stops fixed in the said slot, a fixed stop with which the peripheral stops are designed to engage, the said fixed stop being hinged to allow of its being moved into, or out of, the path of the peripheral stops when the tool holder is rotated, and an eccentric upon which the said fixed stop is pivoted.

5. In a semi-automatic lathe the combination with the headstock and a spindle

mounted in the said headstock and adapted to move longitudinally therein of screw-threaded sleeves fixed upon the said mandrel, double ended levers pivoted on opposite sides of the axis of the mandrel and means for simultaneously engaging the said double ended levers at one end or the other with the screw-threaded sleeves.
